SHELL BODY AND METHOD OF MAKING
SAMEDaniel M. Weigel, Detroit, Mich., assignor to The
Standard Products Company, Detroit, Mich.,
a corporation of Ohio

Application November 26, 1942, Serial No. 466,990

1 Claim. (Cl. 29—1.21)

The invention relates to novel and improved body structures for hollow explosive projectiles of light or heavy caliber, and further relates to novel and improved methods of forming, and assembling such shell body structures.

The methods of manufacturing hollow shell bodies, as heretofore practiced while varying somewhat in detail by reason of the projectile size, design, and source of supply, universally involve the development of the shell body from solid stock. Projectiles about three inches in diameter or smaller are machined from solid rod or bar stock, and in the sizes larger than three inches in diameter they are formed from billets by forging, upsetting, or extrusion, followed by a plurality of machining, boring, cutting and/or grinding operations. All such procedures result in a substantial scrap loss in the form of turnings and borings. This is particularly undesirable by reason of the present metal shortage, especially in the high grade steels required for projectile stock. The multiplicity of fabricating and machining operations, both internally and externally of the shell body also entails a considerable loss of time, and in many cases the use of bulky and costly upsetting or extrusion presses or forging hammers.

The difficulties and disadvantages are multiplied in the manufacture of double chambered or multichambered explosive shells which have one or more internal partition walls transversely of their longitudinal axis. The shell interior may carry, for example, a tracer charge and an explosive charge in separate chambers, or, in the case of high caliber shells, the shell may be provided with a relatively slow burning primer charge, in one chamber and an explosive charge in another chamber, the primer charge serving to initiate an explosion when the ordinary fuse or percussion charge fails to work.

One object of the present invention is the provision of a novel and improved shell body structure for hollow projectiles.

A further object is the provision of a shell body of such design and contour that it lends itself readily to simplified cutting, boring, and metal forming methods.

A further object of the invention is the provision of a shell body which can be fabricated by a simplified machining procedure and with greatly reduced scrap metal losses.

A further object of the invention is the provision of a method of manufacturing a shell body from a seamless steel tubular blank of predetermined length, by a series of steps to be described hereinbelow.

A further object is the provision of a method of manufacturing from seamless steel tubing a shell body of the type wherein an internal, transversely disposed partition divides the shell into

two chambers, said method including certain metal cutting and metal deforming steps to be described hereinbelow for securing said partition in position within the shell body.

5 Further objects comprise the provision of hollow shell bodies of the nature described, which can be produced more rapidly, readily, and economically than has hitherto been regarded as feasible by those skilled in the art.

10 Other objects and advantages will become apparent on consideration of the following description, in conjunction with the accompanying drawing in which

Fig. 1 is a longitudinal section of a seamless steel tubular blank for a shell body;

15 Fig. 2 is a cross-sectional view taken on the line 2—2 of Fig. 1;

Fig. 3 is a section similar to Fig. 1 but showing the blank after suitable machining operations;

20 Fig. 4 is a sectional view of an end plug or base plug for the rear end of the shell body;

Fig. 5 is a longitudinal view of the shell body showing the end plug and nose piece or fuse in position at respectively the rear and front ends of the shell, the nose piece or fuse being shown in elevation;

Fig. 6 is a longitudinal sectional view of a partially machined seamless tubular steel blank suitable for a double chambered shell body;

30 Fig. 7 is a central longitudinal sectional view, broken away at the left and right ends of the drawing, showing a further stage in the preparation of the internal cylindrical periphery of the shell body;

35 Fig. 8 is a transverse sectional view taken on the line 8—8 of Fig. 7;

Fig. 9 is an enlarged sectional view of the stepped portion of Fig. 8;

40 Fig. 10 is a view similar to Fig. 7 but showing a spacing disk in position, and also showing the operating head of an upsetter ram or plunger preliminary to heading in the spacing disk;

Fig. 11 is a view similar to Fig. 10 but showing the position of the several elements at the termination of the power stroke of the upsetter ram;

45 Fig. 12 is a longitudinal sectional view of the finished shell body showing the end plug, the spacing disk, and the nose piece in their respectively final positions, the nose piece or fuse being shown in elevation.

Before the present invention is described in detail, it is to be understood that such invention is not limited to the details of construction or the specific arrangement of parts herein illustrated or described, as the invention obviously may take other forms. It also is to be understood that the phraseology or terminology herein employed is for the purpose of description and not of limitation.

55 Figs. 1 to 5 inclusive illustrate successive steps in the development of a single chambered ex-

plosive projectile or tracer bullet from a blank 20 consisting of a length of seamless tubing shown in longitudinal and transverse section respectively in Figs. 1 and 2. Merely using an example, which is in no wise limiting, the illustrations may be regarded as representing the development to final contour of an explosive bullet of low caliber, for instance 20 mm. in diameter. The outside diameter and wall thickness of blank 20 may be suitably selected to ultimately conform to the required specifications, bearing in mind the simple machining operations to be described. The inside diameter of the blank requires no additional machining operations with the exception of the portion extending inwardly a small distance from each end.

As shown in Fig. 3 one end of the blank is given a coniform, slightly convex taper, at 21. The inner periphery of the tapered end is threaded at 22 to receive a fuse plug or nose piece 23 (Fig. 5). The inner periphery of the other end of the blank is machined to a stepped arrangement providing one or more internal annular shoulders 24. An end plug 25 is machined to a stepped contour complementary to that of the tube so as to seat in the stepped portion of the tube. When thus seated by means of a pressed fit, the terminal edge 26 of the tube blank may be spun, rolled, or otherwise turned at 28 into an inset annular groove 27 around the rear edge of the plug as best seen in Fig. 5. The circumferential periphery of the blank may be provided with one or more annular grooves or depressions 29 for carrying a rifling band not shown of relatively soft metal.

While the method just disclosed for the retention of the end plug is simple and efficient, other effective methods will occur to those skilled in the art on consideration of the various requirements of the general construction of which Figs. 1 to 5 are exemplary.

The outside diameter of the blank shown in Figs. 1 to 5 may be machined or ground to final dimensions in familiar fashion. One of the striking advantages of the manner of fabrication of a shell body as here shown is the simplicity of the procedure, the elimination of a number of diverse forming and shaping steps, and the considerable saving of metal which formerly was lost as turnings, boarings, etc.

Figs. 6 to 12 inclusive illustrate successive steps in the development of a dual chambered shell body from a tubular blank, such as that shown in Figs. 1 and 2, to a finished shell as shown in Fig. 12. A shell of the type shown in Fig. 12 is generally of heavier caliber than the type described in connection with Figs. 1 to 5.

In the manufacture of a dual chambered shell body such as will now be described, a seamless steel tubing is cut to a blank 20 of the proper diameter, length, and wall thickness such as shown in Fig. 1. The blank is provided with a slightly convexed coniform taper 21 at its outer front end, and with an internally threaded portion 22 on its inner front end. It may likewise be provided with rifling band grooves 29, and may be machined or ground to accurate external contour as already described with respect to the prior, single chambered embodiment.

A multiple step reamer (not shown) is inserted from one end, here shown as the front end, to reduce the wall thickness in two successive steps and form three coaxial, adjacent bore portions of increasing diameter, 35, 36 and 37, this machining operation coming to a stop intermediate

the ends of the blank so as to leave two internal annular shoulders 38 and 39, transversely disposed with respect to the tube bore, as shown in Fig. 7, and in enlarged section in Fig. 9.

5 A spacer or disk 40 of a thickness somewhat less than the longitudinal extent of the intermediate bore 36 and of a diameter sufficient to be seated by a press fit in peripheral contact with bore 38 and having a circumferential portion of one face 10 in contact with shoulder 38, is inserted to the position shown in Fig. 10. A plunger or ram 41 having a driving head portion in slidably fitted relationship to bore 37 is advanced from the open end of bore 37 into abutting contact with shoulder 39 of intermediate bore 36 (Fig. 10). Further advance of the ram (Fig. 11), under pressure developed hydraulically or otherwise as is familiar to those skilled in the manner of operation of power presses, causes the shoulder metal 39 of bore 36 to be inturned (Figs. 11 and 12) to provide a permanently positioned inwardly extending retaining flange 42 which locks disk 40 in place as a bulkhead to divide the bore of the blank into two spaced chambers 43 and 44, chamber 43 being of greater diametrical extent than chamber 44. The manner of retention and support to the blank in suitable dies during this flange upsetting operation needs no illustration since familiar to those skilled in the art of fabrication and mechanical deformation of metals.

30 As compared with the present standard method of machining shell bodies of this character from forged billets, or laboriously effecting gradual development of the contour by successive piercing and upsetting operations, the simplicity of the present operation and its economic advantages are immediately apparent.

35 A suitable end plug or disk 46 of any desired character is affixed in the shell base, and a nose piece or fuse 47 is attached at the front end. In this dual chambered embodiment the percussion charge or tracer charge is placed in the chamber 44 before finally affixing the disk or plug 46 in place. The thickness and general characteristics 40 of the disk 46 are determined by the requirements as to size and type of shell, and its intended purpose.

45 While I have described the several simple machining operations in a specific sequence, it is of course obvious that the order of some of the operations may be varied or transposed, and that two or more of said operations may be carried on simultaneously so as to further facilitate the operation, and increase the rate of production.

50 55 What I claim is:

55 A method of making a body for an explosive shell comprising cutting a blank of predetermined length and dimensions from seamless steel tubing, increasing the internal bore diameter of said blank throughout a portion of its length to form three coaxial, adjacent, stepped bore portions and two transversely extending annular shoulders, disposing a spacing disk transversely within said blank in peripheral contact with the intermediate bore wall and having a circumferential portion of one face in contact with the smaller one of said shoulders, and upsetting metal from said intermediate bore wall to form an inwardly extending retaining flange abutting a circumferential portion of the other disk face whereby the shell body is provided with two chambers separated by said disk, one of said chambers being of greater cross sectional diameter than the other.

DANIEL M. WEIGEL.
